UNITED STATES PATENT OFFICE.

THURMAN A. CAMPBELL, OF CHICAGO, ILLINOIS.

STEREOPTICON.

1,318,541.

Specification of Letters Patent.

Patented Oct. 14, 1919.

Application filed June 17, 1918. Serial No. 240,456.

To all whom it may concern:

Be it known that I, THURMAN A. CAMPBELL, a citizen of the United States of America, and a resident of Chicago, in the 5 county of Cook, State of Illinois, have invented certain new and useful Improvements in Stereopticons, of which the following is a specification.

This invention relates to that type of 10 stereopticons or magic lanterns in which compactness and ready portability are requisite features, and has for its object:

To provide a simple and durable structural formation and association of parts 15 adapted to afford compactness, and provide means for storing a supply of lantern slides and other usual accessories of the apparatus, all as will hereinafter more fully appear.

In the accompanying drawing:

20 Figure 1 is a longitudinal sectional elevation of a stereopticon embodying the present improvements.

Fig. 2, is a detail transverse section on line X^2-X^2 , Fig. 1,

25 Fig. 3, is a detail horizontal section on line X^3-X^3 , Fig. 2.

Like reference numerals indicate like parts in the different views.

Referring to the drawing, 1 designates the 30 inclosing casing or housing of a narrow rectangular box form and provided with a carrying handle for convenience in transportation. One side of the casing is open and provided with a hinged door 3 to afford 35 convenient access to the various parts and elements disposed in the interior of the casing.

40 4 designates a vertically elongated opening or passage having a hinged door 5. Said opening is formed in the wall of the casing 1 opposite to the open side of the casing, and is adapted to receive the slide carrier herein- 45 after described, in the actual use of the apparatus.

45 6 designates the lamp house of the usual rectangular form, disposed in the upper portion of the rear part of the casing 1 and containing the usual incandescent electric lamp 7 or like source of illumination.

50 8 designates the usual condenser casing associated with the front wall of the lamp house 6, and carrying a pair of condenser lenses 9 and with the usual transverse skeleton holding frame 10 disposed in transverse 55 alinement with the aforesaid opening 5 of the main casing and adapted to support in

proper operative position the stationary member of the slide changer hereinafter described, and which is clamped in place by a set screw 11, as illustrated in Fig. 1. 60

In the present structure the front wall of the casing 1 is disposed a distance in front of the lamp house 6 and its accessories, so that an extended front space in the interior of the casing is provided and which is 65 adapted to receive an extra lantern slide box or other usual stereopticon accessory, when the apparatus is not in use or packed for storage or transportation.

12 designates an opening formed in the 70 aforesaid front wall of the main casing 1 in line with the optical axis of the condenser lenses 9 and adapted to permit the passage of the light rays from said condenser lenses to the objective 13 of the apparatus. 75

14 designates a door or cover adapted to close the opening 12 aforesaid. In the present improvement said door constitutes the support for the objective 13, and is in turn supported and slidingly guided by the following means:

15 designates one or more depending guide brackets secured to the under side of the top wall of the main casing 1 and adapted for sliding engagement with a longitudinally arranged rod or bar 16, the forward end of which is secured to the door or cover 14, preferably by an angular extension as shown, to constitute the sole support for the door 14 and associated objective 13. 85

17 designates a set screw associated with the bracket 15 and sliding rod 16, to secure said rod at the point to which it is adjusted in the operation of focusing the objective 13. 90

18 designates a horizontal partition ar- 95 ranged midway the height of the main casing 1 and extending from the front wall of said casing to the lamp house 6 to constitute the top wall of a containing chamber for a supply of the lantern slides used with the apparatus. With a view to afford separated relation to the series of such lantern slides the under surface of the partition 18 and the upper surface of the bottom wall of the casing 1 are formed with a series of closely ar- 100 ranged channels adapted to receive a corresponding series of transverse partitions 19 and provide the usual series of individual containing chambers for the lantern slides. 105

20 designates the stationary skeleton 110 frame of a slide changer of any usual and suitable construction adapted to fit the

skeleton holding frame 10 heretofore described, and in which said stationary frame is held in place by the set or clamping screw 11 aforesaid.

5 21 designates the usual lantern slide carrying frame of the usual elongated skeleton form and adapted to have sliding movement in the aforesaid stationary frame 19 to carry the lantern slides into and out of the light 10 path of the apparatus. In actual use the respective doors 3 and 5 heretofore described will be opened so that the slide changer may be arranged in the door openings for convenient and free manipulation.

15 Having thus fully described my said invention what I claim as new and desire to secure by Letters Patent, is:—

20 1. In a stereopticon of the type described the combination of a main inclosing casing 20 of a rectangular box form and having an open side, a lamp house arranged in the upper rear end of the casing leaving a clear space therein in front of the lamp house, a condenser and a skeleton frame associated 25 with said lamp house, the wall of the main casing opposite to the aforesaid open side having an opening in line with said skeleton frame, a slide changer supported by said skeleton frame a projecting lens arranged at 30 the front end of the space aforesaid, and a horizontal partition arranged midway the

height of the main casing and extending from the front wall of the same to the lamp house and providing a containing chamber for accessories of the stereopticons, substantially as set forth. 35

2. In a stereopticon of the type described, the combination of a main inclosing casing of a rectangular box form and having an open side, a lamp house arranged in the upper rear end of the casing leaving a clear space therein in front of the lamp house, a condenser and a skeleton frame associated with said lamp house, the wall of the main casing opposite to the aforesaid open side 40 having an opening in line with said skeleton frame, a slide changer supported by said skeleton frame, a projecting lens arranged at the front end of the space aforesaid, a horizontal partition arranged midway the height of the main casing and extending from the front wall of the same to the lamp house, and a series of vertical partitions arranged between said partition and the bottom wall of the main casing to provide a 45 series of individual containing chambers for accessories of the stereopticons, substantially as set forth. 50

55 Signed at Chicago, Illinois, this 15th day of June, 1918.

THURMAN A. CAMPBELL.
